DESIGN FOR A KNIFE OR SIMILAR ARTICLE

Vilhelm Hingelberg, Aarhus, Denmark

Application December 10, 1946, Serial No. 135,386

Term of patent 14 years

(Cl. D54—12)

To all whom it may concern:

Be it known that I, Vilhelm Hingelberg, a citizen of Denmark, residing in Aarhus, Denmark, have invented a new, original, and ornamental Design for a Knife or Similar Article, of which the following is a specification, reference being had to the accompanying drawing, forming a part thereof, in which:

Fig. 1 is a side elevational view of a knife or similar article, showing my new design;

Fig. 2 is an edge elevational view thereof as seen when looking from the right of Fig. 1; and

Fig. 3 is an elevational view of the opposite side of Fig. 1.

The essential features of my design reside in the configuration and ornamentation of the handle shown in full lines.

I claim:

The ornamental design for a knife or similar article, as shown and described.

VILHELM HINGELBERG.
